CLASP

Arthur A. Johnson and Herbert G. Lehmann,
Bridgeport, Conn., assignors to The Red Star
Company, Bridgeport, Conn., a corporation of
Connecticut

Application May 1, 1948, Serial No. 24,485

3 Claims. (Cl. 24—186)

1

The present invention relates to an improvement in clasps and, as herein disclosed, the improvements are embodied in clasps which are adapted primarily for use in securing in position the ends of a strip of loosely woven fabric such as the gauze within which the absorbent element of sanitary pads are commonly encased.

It has been the usual practice to retain the ends of this gauze to suitable suspension elements by various types of buckles, clasps or like attaching means, but in the main such prior devices do not afford the security demanded in this field and, in addition, the fastening is difficult to attain.

It is an object of the present invention to provide a clasp or fastener of the character described, which securely retains the ends of the pad from accidental removal, but which permits the fabric ends to be readily attached or detached.

Another object of the invention is to provide a device of the character set forth having novel means for threading the end of a sanitary napkin therein.

A further object of the invention is to provide a device of the character set forth having novel means for ensuring the penetration of spears forming a part of the invention into a sanitary napkin.

Other and further objects of the invention will be apparent from the following specification, taken in conjunction with the drawings, in which:

Figure 1 is a front elevational view of an embodiment of the invention;

Fig. 2 is a view similar to Figure 1, but showing a portion of a sanitary napkin secured thereto; and

Fig. 3 is a side elevational view of Figure 2.

Generally there is provided a clasp for catamenial diapers or sanitary napkins, which comprises a single piece of flat material having a transversely extending eye for the reception of a strap or the like dependent from a sanitary belt of conventional character. The clasp is also provided with a second eye having an entrance throat at the side of the clasp. The latter eye is provided with spear-shaped teeth which extend at an angle to the horizontal from the lower inner edge of the eye.

Referring more particularly to the drawings, there is shown therein a sanitary napkin clasp comprising a single piece of flat material having a relatively narrow upper edge 10 and a relatively wide lower edge 11.

Adjacent the upper edge 10, there is provided

5 a narrow transversely extending eye 12 adapted to receive a strap 13 of a sanitary belt. In the greater part of the lower portion of the clasp there is provided an eye 14 having an entrance throat 15 communicating with the upper end and the outer side of the clasp.

The lower inner edge of the eye 14 is at an angle to the horizontal and is provided with spear-like teeth 16 and 17. It will be noted that 10 the tooth 16 is, therefore, higher than the tooth 17.

The throat 15 is located a substantial distance above the teeth 16 and 17 and the inner edge of the clasp opposite the throat defines an arc 19.

15 The end of the arc nearest the eye 10 terminates in a short rounded dependent portion 20 forming one wall of the throat 15. From this point, the arc continues to form a first necked portion 22 on one side of the first tooth 16. A second 20 necked portion 23 disposed at an angle to the horizontal to the first neck 22 is located on the other side of the tooth 16, while a third necked portion 24 is likewise disposed at an angle to the horizontal to both necked portions 22 and 23. The 25 necked portion 24 terminates in an upstanding elongated arm 25, which is upwardly and inwardly inclined to form the other wall of the throat 15.

In operation, it will be apparent that the clasp may be attached in conventional manner to the 30 strap 13 by utilizing the eye 12. Thereafter, when the belt is in position upon the user's body (it being contemplated, of course, that two of the devices, one in front and one in back, are used in actual practice), an end 18 of a sanitary napkin assembly is introduced into the clasp by 35 passing the same through the entrance throat 15 and is guided by the arc portion 19 and is then brought downwardly against the teeth 16 and 17. It will be apparent that the tooth 16, being higher, 40 will first come into contact with the gauze end 18 and will penetrate the same easily due to the fact that but one point is presented against the downward pull upon the napkin. Thereafter, the tooth 17 will individually come into contact with 45 the gauze to penetrate the same. If both teeth were of the same height, considerable pressure or downward pull would be necessary to penetrate the gauze and the addition of more teeth, if all of the same height, would in turn correspondingly 50 increase the downward pull required to penetrate the gauze. On the other hand, if a single tooth were employed, this would provide only limited engagement with the gauze and probable accidental unfastening. Thus, the present construction attains the security attendant on using more

than one tooth, but without the amount of downward pull required in assembling the gauze ends on the fastener.

By providing an entrance throat 15 for the napkin tab, the latter may be inserted without threading as is ordinarily done, and, after the gauze is caught on the teeth, one or more turns may be taken around the body of the clasp by merely passing the end of the gauze repeatedly through the throat 15. The provision of a laterally open clasp has the further advantage that if in use the gauze should stretch, it is merely necessary for the user to take another turn or hitch about the body of the clasp by passing the portion of the gauze between the 15 clasp and the pad through the entrance opening 15, thereby shortening the length of the assembly.

The depending portion 20 in cooperation with the upwardly and inwardly inclined arm 25 prevents any inadvertent movement of the gauze from the opening within the clasp attendant upon the slackening of the gauze as when the user sits. If the gauze should tend to rise and become released from the barbs 16 and 17, it would be caught by the overhanging portion 25 before it escaped through the opening 15. Thus, it will be seen that for the gauze to escape from the aperture in the clasp it must follow a tortuous path upward to the left and then to the right around the arm 25 and then down past the depending arm 20. On the other hand, when the tab is to be removed from the clasp, when the gauze is unwrapped from the body portion 11, each turn may be guided through this tortuous path manually through the entrance opening 15 without undue interference from the projecting portion 20 and the vertical arm 25.

Variations and modifications may be made within the scope of this invention, and portions of the improvements may be used without others.

We claim:

1. A device of the character described comprising a plate having an upper mounting aperture, a large tab-receiving aperture defined by the top of the plate, side strips and a bottom bar, and tab-impaling barbs on the bottom bar lying in said aperture, one of said side strips having a slot forming a passage for the tab, said slot being intermediate the ends of said side strip so as to form upper and lower lugs pre-

5

venting the inadvertent removal of the tab from the aperture, the slot being near the upper portion of the side strip whereby the lower lug is longer than the upper lug, and the lower lug being curved in towards the center of the aperture.

2. A device of the character described comprising a plate having an upper mounting aperture, a large tab-receiving aperture defined by the top of the plate, side strips and a bottom bar, and tab-impaling barbs on the bottom bar lying in said aperture, one of said side strips having a slot forming a passage for the tab, said slot being intermediate the ends of said side strips so as to form upper and lower lugs preventing the inadvertent removal of the tab from the aperture, the slot being near the upper portion of the side strip whereby the lower lug is longer than the upper lug, said lower lug curving inwardly toward the center of the aperture.

3. A device of the character described comprising a plate having an upper mounting aperture, a large tab-receiving aperture defined by the top of the plate, side strips and a bottom bar, and tab-impaling barbs on the bottom bar lying in said aperture, one of said side strips having a slot forming a passage for the tab, said slot being intermediate the ends of said side strip so as to form upper and lower lugs preventing the inadvertent removal of the tab from the aperture, the slot being near the upper portion of the side strip whereby the lower lug is longer than the upper lug, and extends inwardly so as to overlie at least one of the barbs.
